ATTORNEY

WITNESS:

UNITED STATES PATENT OFFICE.

JAMES SAUL MCLEAN, OF ALBUQUERQUE, NEW MEXICO, ASSIGNOR OF FORTY-NINE PER CENT TO ROBERT F. JOHNSTON, OF ALBUQUERQUE, NEW MEXICO.

SIGNAL.

Application filed January 21, 1927. Serial No. 162,526.

This invention relates to a signal for vehicles and the like, the general object of the invention being to provide means for indicating when the vehicle is to be turned to the left or right or is to be stopped, with means whereby the signals can be seen from both the front and rear as well as from the sides of the vehicle.

Another object of the invention is to place the signals on strips of cloth or similar material and to wind the strips upon rollers, one roller of each pair being a spring roller which normally holds the strip in wound condition, with a blank space appearing at the window of the signal casing, with means for rotating the other roller of the pair to wrap part of the strip thereon and thus bring a portion of the strip having a signal word thereon in front of the window.

Another object of the invention is to provide manually operated means for operating the signal means from a point adjacent the driver's seat.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a view showing the signal in use on a motor vehicle.

Figure 2 is a view of the hand operated means for actuating the signal.

Figure 3 is a sectional view with parts broken away of such means.

Figure 4 is a section on line 4—4 of Figure 2.

Figure 5 is a view of one of the signal casings.

Figure 6 is a vertical sectional view through such casing.

Figure 7 is a section on line 7—7 of Figure 5 and showing both casings.

Figure 8 is a section on line 8—8 of Figure 6.

Figure 9 is a longitudinal sectional view through one of the spring rollers.

In these views, 1 and 2 indicate a pair of signal casings which are arranged at right

angles to each other, with one corner of a casing abutting a corner of the other casing, as clearly shown in Figure 7. The inner corners of the casings are suitably arranged adjacent the left hand front post of the body of the vehicle, as shown in Figure 1 and the casings are suitably supported in this position. It will, of course, be understood that the casings could be placed at other points on a vehicle, though they should be so placed that the signals of one casing can be seen from the front and rear of the car and the signals of the other casing can be seen from the sides of the car.

Each casing has a window 3 in each side thereof, the windows being closed by transparent members 4. An electric lamp 5 is also placed in each casing for illuminating the signals at night, these lamps being suitably connected with the battery of the car or other suitable source of current. A pair of spring rollers 6 is arranged in the inner end of each casing, each roller being rotatably mounted on a shaft 7 and a coiled spring 8 is arranged in each roller and has one end connected to the roller and the other end to the shaft. Thus when the roller is rotated, the spring will be contracted and said spring will return the roller to its normal position. A pair of rollers 9 is arranged in the outer end of each casing and a pulley 10 is fastened to the lower part of each roller 9. A strip 11 of cloth or the like is fastened to each of the rollers 6 and to each of the rollers 9, each strip passing across the window in rear of the transparent member 4. Guides 12 are provided for the strips to keep them adjacent the windows. Each strip has thereon the words "Right", "Left" and "Stop" and a blank space which will appear at the window when the spring 8 has moved the roller 6 to its normal position but when the roller 9 is rotated, by means hereinafter to be described, a portion of the strip will be wound upon said roller 9 and drawn from the roller 6 so that one of the words will appear at the window, as shown in Figures 1 and 5.

A belt 13 is fastened to each pulley 10 and the belts from each pair of rollers 9 are connected to a cable 14. The cables 14 from the two casings pass through the branches 15 of the tube 16 into said tube where one of the cables is fastened to the other and then the long cable is fastened to a lever 17 which

is pivoted to a segment 18 which is arranged in the car adjacent the driver's seat so that the driver can move the lever to operate the cables and thereby the rollers 9 through 6 means of the belts 13. The segment is provided with notches 19 for receiving a spring latch 20 carried by the lever and provided with a notch 21 for holding the lever in adjusted position. Each notch is designated 10 with a legend, the legends corresponding with the words on the strips 11 and one notch having the legend "Clear go" and when the lever is in this position, the blank parts of the strips 11 will be at the windows. I prefer to provide a curved passage 22 in the segment 18 through which the cable 14 passes and to extend a bent end 17' of the lever into said passage so that the cable can be attached to said bent end. 15

20 From the foregoing it will be seen that when the driver wishes to turn to the left or right or is to stop or slow up, he can indicate his intentions by simply grasping the handle 21 to retract the latch and then move 25 the lever 17 to the place on the segment, the legend of which states what he is to do. This action of the lever will pull upon the cables 14 and the belts 13 so that the rollers 9 will be rotated to adjust the strips 11 to a 30 position where the words thereon which are the same as the legend over which the lever has been moved will appear through the windows so that persons observing the signals will know just what the driver intends 35 to do. After his intentions have been carried out, the lever is moved over to the "Clear go" notch so that the springs of the spring rollers will return the parts to normal position with the blank spaces on the strips appearing at the windows. Of course, if desired, the words "Clear go" or similar words can be placed on these blank spaces of the strips. 40

45 It is thought from the foregoing description that the advantages and novel features of my invention will be readily apparent.

50 I desire it to be understood that I may make changes in the construction and in the combination and arrangement of the several parts, provided that such changes fall within the scope of the appended claims.

What I claim is:—

1. A signal of the class described comprising a casing having a window therein, a spring roller in one end of the casing, a 55 second roller arranged at the other end of the casing, a belt having its ends fastened to the rollers, said belt carrying signal words, a pulley on the second roller, a flexible member wound thereon and extending 60 into the vehicle for rotating the second roller from the interior of the vehicle to move the belt to a position where one of the signal words thereon will appear at the window. 65

2. A signal of the class described comprising a casing having a window therein, a spring roller in one end of the casing, a second roller arranged at the other end of the casing, a belt having its ends fastened to the 70 rollers, said belt carrying signal words, means for rotating the second roller from the interior of the vehicle to move the belt to a position where one of the signal words thereon will appear at the window, such 75 means comprising a pulley fastened to the second roller, an operating lever in the vehicle, flexible means connecting the same with the pulley, a dial over which the lever operates and means for holding the lever in 80 adjusted position.

3. A signal of the class described comprising a pair of casings arranged at right angles to each other with the corner of one casing abutting the corner of another casing, each casing having a window in each face thereof, a pair of spring rollers in the inner end of each casing, a pair of rollers in the outer end of each casing, a belt having its ends connected with a roller of each pair of spring rollers and with a roller of each of the other pair of rollers, said belt having signal words thereon for appearing at the window, a pulley on each of the second rollers, a belt connected with each pulley, the belts of each roller of each pair being connected together, a cable connected with each pair of belts and means attached to the cables for rotating the second rollers to adjust the belts in front of the windows. 95 100

In testimony whereof I affix my signature.
JAMES SAUL McLEAN.
